UNITED STATES PATENT OFFICE.

JOSEPH LOUIS PHILIPPE LANDRY, OF MONT JOLI, QUEBEC, CANADA.

DESIGN FOR A HEADLIGHT-BRACKET.

54,935.

Specification for Design.

Patented Apr. 20, 1920.

Application filed March 21, 1919. Serial No. 284,217. Term of patent 14 years.

To all whom it may concern:

Be it known that I, JOSEPH LOUIS PHILIPPE LANDRY, a subject of the King of Great Britain, residing at Mont Joli, in the Province of Quebec and Dominion of Canada, have invented a new, original, and ornamental Design for a Headlight-Bracket, of which the following is a specification, reference being had to the accompanying drawing, forming a part thereof.

Figure 1 is a perspective view of the head-

light bracket showing my new design in operative position.

Fig. 2 is a horizontal section through the same.

I claim:

The ornamental design for a headlight bracket, as shown.

JOSEPH LOUIS PHILIPPE LANDRY.
